US0D1039840S

(12) **United States Design Patent** (10) **Patent No.:** **US D1,039,840 S**
(45) **Date of Patent:** **** Aug. 27, 2024**

(54) **ORGANIZER BOX**

(71) Applicant: **Fujian Zhenghe County Boyi Bamboo Industry Co., Ltd.**, Fujian Province (CN)

(72) Inventor: **Dongpeng Wu**, Zhenghe County (CN)

(**) Term: **15 Years**

(21) Appl. No.: **29/931,287**

(22) Filed: **Mar. 6, 2024**

(51) LOC (14) Cl. **09-04**

(52) U.S. Cl.

USPC **D3/313**; D3/304

(58) **Field of Classification Search**

USPC D3/20, 23, 201, 304, 313, 314, 319; D6/628, 629, 682.2, 682.4; D7/553.1, D7/553.2; D9/756, 759, 760; D16/250

CPC ... A47F 7/02; A47F 7/022; A47F 7/12; A47G 25/00; A47G 25/74
